LIFT

Otto Merkel, Hawthorne, N. Y.

Application June 11, 1949, Serial No. 98,587

5 Claims. (Cl. 187—19)

1

The invention comprehends a lift.

The carrying or lifting of aged, infirm, invalid persons, or weighty articles from one level to another, is a difficult, well-nigh impossible task particularly in the case of invalids, since the added weight and bulk of a wheel chair adds to the inherent difficulties. In fact, an invalid must oft-times stay either permanently up or down-stairs, even in homes which are equipped with an elevator for stairs, if a stair landing is interposed between the top of the stairs, or second floor, and the first. An example of a stair elevator of the type referred to is, by way of example disclosed in Patent Number 1,358,062 dated November 9, 1920.

One object of my invention is the provision of a lift which will lift and return invalid, aged or infirm persons from one level to another with ease and dispatch, as for example, from the floor level to a stair landing and vice-versa.

Another object comprehends a lift, which may be used in connection with a bridge, if desired, for lifting invalids or weighty objects from floor level to the platform of a stairway elevator, such as is disclosed in Patent Number 1,358,062.

A further object of the invention is a lift which can be controlled and caused to move from one extreme position to another from a position remote the lifting mechanism.

An additional object is a lift, the platform of which becomes part of the floor when in lowered position, and the lifting mechanism of which can be positioned and mounted therebeneath, on the supporting beams affixed therebelow, without undue disturbance of or change of existing house structure.

Briefly described, the lift includes a platform, which when lowered, is positioned and rests level with the adjacent flooring and forms part thereof, said platform mounted on a base plate which is fixedly mounted on a mechanism positioned therebelow and remotely controlled, for lifting and lowering the platform. A bridge may be provided, for use in certain locations.

In the drawings:

Fig. 1 is an elevation of the lift in retracted position, with the platform thereof forming part of the floor.

Fig. 2 is an elevation of the lift applied to a practical use, adjacent a stair landing.

Fig. 3 is an elevational view of the lift in retracted position.

Fig. 4 is an elevational view of the raised lifting device.

Fig. 5 is a front elevational view of Fig. 4 showing the lifting means.

2

The lift comprises a platform 5 mounted on table-like base 6, as by bolts 7. The platform, fabricated of plywood, or other material having the desired structural characteristics, preferably is of sufficient dimension to accommodate a wheel chair or other bulky object with ease, while base 6 is preferably a steel or other metal plate.

Mounted beneath the base 6, and secured thereto as by welding, is a rigid skeleton supporting frame 8 having plate 9 spaced below said base and a plurality of cross-braces 10 therebetween.

Rigidly affixed to and extending vertically beneath frame 8 are two pairs of plate-like extensions 11 and 12. A pair of elongated arms 13 are journaled at one end on the pair of extensions 11, as by studs, and extend downwardly therefrom at an oblique angle relative to frame 8. Rollers 14 are journaled at the free ends of the arms 13, and the latter are rigidly connected together, intermediate their ends, by the cylindrical braces 15 and 16. The brace 16 is provided with a rod 16' extending therethrough and through the arms 13 so that the opposite ends of the rod 16' extend outwardly from the sides of the arms. On these opposite ends are pivoted another pair of arms 17, the lower ends pivoted to plates 18, rigidly mounted on bed plate 19.

Welded or otherwise secured to the outer sides of arms 17 are upwardly extending plates 20 to which are pivoted as at 21 links 22, the other ends of which are pivoted to plate-like extensions 12.

Toward one end of base 6, and extending therebeneath is another pair of depending extensions 23, to which are pivoted, as at 24, a pair of links 25, the lower ends of which are pivoted, at 26, to arms 17. These links are dimensioned to maintain level the platform 5 as the lift is raised and lowered, and prevent wobbling.

To the outer ends of arms 17 is rigidly secured, at 27, a yoke 28, to the underside of which is pivotally secured the head of piston 29, of hydraulic jack cylinder 30. The latter is mounted on channel-like plate 31, secured between arms 13, and has connected thereto a tubing 32, connected to hydraulic fluid pump 33, having pump handle 34.

In order to obviate undue disturbance of existing house structure, and as a firm base support for the lift, bed plate 19 is formed at one end with a pair of obliquely angled extension 35 with flanges 36, while the other end is provided with lower side walls 37, vertical extension 38 and flange 39. The construction of the bed plate only requires the attachment of beams or supports B to the existing floor beams, as a frame for said

plate, since flanges 36 and flange 39 can be rigidly secured to and rest upon said beams and a firm rigid support is thereby formed.

When in retracted position depicted in Figs. 1 and 3, platform 5 becomes part of the adjacent flooring F, with the sub-flooring being indicated by the letter S. There is no disturbance of floor area, with the pump 33 positioned adjacent a stairway, in the application of the invention illustrated herein.

If it is desired, for example, to use a stairway elevator of the type illustrated in Patent Number 1,358,062, with a stairway landing L interposed between the floor and stairs S', an invalid may be wheeled on the platform 5, pump handle 34 actuated, after fluid valve 40 is closed, raising the platform level with the stair landing. In operation hydraulic fluid is forced through tubing 32, into cylinder 30, expanding piston 29 to force yoke 28 upwardly, through the opposing action of the base of cylinder 29 operating against plate 31. With the opposite ends of arms 17 on fixed pivot points 18, the upper ends of arms 13 are caused through the cooperating movement, to lift the platform 5 as rollers 14 move inwardly of extension 33.

With the platform in elevated position, as shown in Figs. 2 and 4, a hinged bridge B' may be employed to bridge the gap between the edge of the platform and the stair landing, and, as indicated in Fig. 2, the movement of the rollers 14 away from extension 38 is more than compensated for by the opposite travel of the arms 13.

After the invalid is moved from the platform 5 to the stair landing, valve 40 may be opened, retracting the lift so that platform 5 again forms part of the flooring.

The invention may be employed not only for lifting invalids to stair landings, but for elevating weighty objects in any desired location where the lift may be secured. Means other than hydraulic, such as compressed air, may be employed, and I desire to make such changes or modifications as may come within the scope of the appended claims.

I contemplate, for example, that the lifting means between base 6 and plate 19 may be a telescopic ram hydraulic lift, or an expanding device in the nature of a parallel bar expanding grille, or gate, or any lifting means which can be mounted between the platform and base without undue disturbance of a house structure and capable of being mounted between, but not below existing floor beams.

I claim:

1. A lift comprising a support having extending flanges, a pair of arms each pivotally secured at one end to one end of the support and a yoke secured to the other ends of said pair of arms, a second pair of arms rigidly jointed together intermediate their ends by braces, one of said braces having a rod journalled therethrough and pivotally carrying the first pair of arms intermediate their ends, the second mentioned pair of arms having mounted thereon at one end a frame and base thereabove carrying a platform, the other end of the latter pair of arms having journalled thereon a pair of rollers movable on the support and a plate secured between the ends, a fluid operated cylinder and cooperating piston between the yoke and base plate, links pivoted between the arms and the said frame and support, and a fluid pump having a valve operable remote the lift for controlling movement of the pistons.

2. A lift for positioning in the same plane as and beneath a floor having floor beams therebeneath, including: a support having a pair of flanges at one end and a flange at the other end, said flanges adapted to rest on and be secured to structure attachable to but not extending below the floor beams; a pair of arms each having one end pivotally secured to one end of the support and a yoke secured to the other ends of said pair of arms; another pair of arms rigidly joined together by braces, one of said braces having a rod journalled therethrough and having the other pair of arms pivoted thereon intermediate their ends; the second mentioned pair of arms having pivoted thereto at one end a frame and base thereabove carrying a platform, the other end having journalled thereon a pair of rollers and a plate secured between the ends; a fluid operated cylinder and cooperating piston between the yoke and base plate; links pivoted between both pairs of arms and the said frame and support; a valved pump connected to the cylinder operable remote the lift to extend and retract the piston.

3. A lift for positioning in the same plane as and beneath a floor having floor beams therebeneath, including: a support having a pair of flanges at one end and a flange at the other end, said flanges adapted to rest on and be secured to structure attachable to but not extending below the floor beams; a pair of arms each having one end pivotally secured to one end of the support and a yoke secured to the other ends of said pair of arms; another pair of arms rigidly joined together by braces, one of said braces having a rod journalled therethrough and having the other pair of arms pivoted thereon intermediate their ends; the second mentioned pair of arms having pivoted thereto at one end a frame and base thereabove carrying a platform, the other end having journalled thereon a pair of rollers and a plate secured between the ends; a fluid operated cylinder and cooperating piston between the yoke and base plate; linkage between both pairs of arms and the said frame and support; connecting means operable remote the lift to extend the piston whereby the yoke and base plate are spread apart to cause the ends of one pair of arms carrying the frame, base and platform to lift.

4. A lift for positioning in the same plane as and beneath a floor having floor beams therebeneath, including: a support having a pair of flanges at one end and a flange at the other end, said flanges adapted to rest on and be secured to structure attachable to but not extending below the floor beams; a pair of arms each having one end pivotally secured to one end of the support and a yoke secured to the other ends of said pair of arms; another pair of arms rigidly joined together by braces, one of said braces having a rod journalled therethrough and having the other pair of arms pivoted thereon intermediate their ends; the second mentioned pair of arms having pivoted thereto at one end a frame and base thereabove carrying a platform, the other end having journalled thereon a pair of rollers and a plate secured between the ends; a fluid operated cylinder and cooperating piston between the yoke and base plate; linkage between both pairs of arms and the said frame and support; a fluid pump connected to the cylinder and operable remote the lift to extend the piston whereby the yoke and base plate carrying opposing ends of the pairs of arms are spread

apart to cause the other ends of one pair of arms carrying the frame, base and platform, to lift.

5. A lift for positioning in the same plane as and beneath a floor having floor beams therebeneath, including: a support having a pair of flanges at one end and a flange at the other end, said flanges adapted to rest on and be secured to structure attachable to but not extending below the floor beams; a pair of arms each having one end pivotally secured to one end of the support and a yoke secured to the other ends of said pair of arms; another pair of arms rigidly joined together by braces, one of said braces having a rod journalled therethrough and having the other pair of arms pivoted thereon intermediate their ends; the second mentioned pair of arms having pivoted thereto at one end a frame and base thereabove carrying a platform, the other end having journalled thereon a pair of rollers and a plate secured between the end; a fluid operated cylinder and cooperating piston

between the yoke and base plate; linkage between both pairs of arms and the said frame and support; connecting means operable remote the lift to extend the piston whereby the yoke and base plate carrying one of the ends of both pairs of arms are spread apart to cause the other ends of one pair of arms carrying the frame, base and platform, to lift, the linkage between both pairs of arms and the said frame and support maintaining the platform level as it is lifted.
